(57) **CLAIM**

The ornamental design for an electric vegetable processor as shown and described.

DESCRIPTION

FIG. 1 is a front elevational view of an electric vegetable processor, showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a top, front, perspective view thereof.

The broken lines showing portions of the article form no part of the claimed design.

1 Claim, 7 Drawing Sheets
